UNITED STATES PATENT OFFICE.

EDWARD D. LEVY, OF SPRINGFIELD, MISSOURI, AND BURTON W. MUDGE, OF CHICAGO,
ILLINOIS.

SECTION-CAR.

1,227,808.

Specification of Letters Patent. Patented May 29, 1917.

Application filed July 29, 1916. Serial No. 112,058.

To all whom it may concern:

Be it known that we, EDWARD D. LEVY and BURTON W. MUDGE, citizens of the United States, residing at Springfield, in the county of Greene and State of Missouri, and Chicago, in the county of Cook and State of Illinois, respectively, have invented certain new and useful Improvements in Section-Cars, of which the following is a specification.

Our invention relates to railway section cars which are now most frequently operated by gasolene motors and are used for transporting section gangs and their tools and appliances to and from the places where the work on the track is being done. These cars, when motor driven, are often run at high speeds and, as a result of the carelessness of the operators and of the occupants, accidents are not infrequent, due, for example, to the derailing of the car or from the workmen being thrown from the car when a curve is taken at too high a speed. It has also happened that cars of this type have been wrecked and the workmen hurt by the tools falling from the deck of the car upon the track and causing the car to be derailed.

One of the principal objects of our invention is to provide a guard structure for a section car, particularly a motor driven section car, which, while adding little to the weight of the car, an important consideration, as these cars have to be frequently lifted from the rails, will be strong and so designed as to afford as much protection against accident as is possible under the circumstances.

A further object of the invention is to provide an arrangement which will minimize the danger of injury to the workmen when the car is removed from the track. In lifting the car from the rails it may be tilted on one pair of wheels and, where no means of protection is provided, there is likelihood that the hands of the men who have hold of the car at this end may be crushed between the car and the ties or rails. The car of our invention is preferably provided with a hand rail at each end, below which is arranged a guard rail, the latter being of such cross-sectional configuration that it is not convenient to grasp when the car is lifted. Thus the workmen are forced to lay hold of the upper or hand rail, and the lower one or

guard rail will thus protect their hands from being crushed or otherwise injured.

The invention consists in the new and improved arrangements, devices and constructions, to be hereinafter described and claimed, for carrying out the above stated objects, and such other incidental objects as may appear from the following description.

The invention is illustrated in certain preferred embodiments in the accompanying drawings, wherein—

Fig. 1 is a side elevation illustrating a preferred form of the invention;

Fig. 2, an end elevation of the car shown in Fig. 1;

Fig. 3, a sectional view on line 3—3 of Fig. 1;

Fig. 4, a view, in perspective, of the guard structure shown in the preceding figures;

Fig. 5, a fragmentary view, in perspective, of one end of the car frame showing, particularly, the relation of the hand rail and guard rail;

Fig. 6, a view, in perspective, illustrating a modified construction; and

Fig. 7, a detail view showing a possible further modification.

Like characters of reference designate like parts in the several figures of the drawings.

Referring first to Figs. 1 to 4, inclusive, the framework of the car is shown as of ordinary construction consisting of longitudinal members 10 and transverse members 11 on which latter the deck boards 12 are laid, the structure being preferably braced by transverse truss rods 13. 14 are the wheels of the car on the axles 15 on which the framework of the car may be mounted in any suitable manner (not shown). 16 is a bench extending lengthwise of the car and supported on cross-pieces 17 which are laid on stringers 18, the bench being bolted to the cross-pieces, stringers and deck boards by bolts 19.

In order to prevent tools and other articles from falling off the deck, which, as stated, has been the cause of some serious accidents, we preferably provide guard strips 20 along the longitudinal edges of the deck, and similar strips 20^a at the ends of the deck.

Guard structures providing hand-holds are arranged at opposite ends of the car. These structures comprise, preferably in each case, an arched tubular member 21, the

ends 22 of which are bent over, flattened and secured by bolts 23 to the adjacent end guard strip 20^a and transverse frame member 11. The structure comprises further a 5 horizontal tubular brace 24, a pair of vertical braces 25 extending between the horizontal brace and guard strip 20^a and secured to the latter and the end transverse frame member 11 by bolts 26, and a vertical brace 27 between the horizontal brace 24 and the arched member 21, these braces being preferably made of sections of metal piping and secured together in any suitable manner, for example, by welding. Preferably 10 the portions of the guard structures above described, below the horizontal brace 24, are covered with wire mesh netting 28. The arched guard rails 21 are connected by a longitudinal member 29 which extends 20 lengthwise of the car over the center line of the bench, and the structure is further rigidified by suitable diagonal braces, for example, the braces 30 extending from the horizontal braces 24 of the bench.

25 For convenience in lifting the car from the rails, the car is provided at each end with a hand-rail 31 which fits into grooves formed in the projecting extremities of the longitudinal frame members 10 of the 30 car and is bolted to said members by bolts 32. The hand-rail consists, preferably, of a section of metal piping. The guard rail 33 is preferably a flat, relatively thin strip of metal, set diagonally into the lower edges 35 of the frame members 10 and held in place by bolts 32 and wedge shaped washers 34.

Section cars are frequently crowded to the fullest extent. It is at such times that the danger of accident is greatest. Our 40 idea has been to provide a light, strong guard structure for a car of this sort, which will afford as much hand-hold space as possible. The men may take hold of the arched members 21 and also the longitudinal member 29, the latter forming a back when the men are seated on the bench. The inclosure of the end by the wire mesh 28 and the provision of a deck with guard strips 20, 20^a, minimize the chance of tools falling from 45 the car and derailing it.

By the arrangement of the hand rails and guard rails at the ends of the car, there is little likelihood that the men who lift the car from the track will have their hands 55 crushed, as has occurred not infrequently. The shape and position of the guard rail is such that it is difficult to grasp, so that those handling the car are compelled to lay hold of the hand rail.

60 A modification is shown in Fig. 6. In this construction the car 35 is provided with a bench 36, the seat portion of which extends beyond the ends of the deck of the car. The guard structure at each end of the 65 car consists of an arched member 37, a hori-

zontal brace 38, a vertical brace 39, the lower end of which 40 is secured to the bench. The spaces between the arched member and the bench are protected by pieces of wire mesh 41 secured to the guard structures and on their inner edges to the bench. Cross-strips 42 are placed across the end openings of the bench so as to minimize the danger of tools that may be placed under the bench falling from the car. The longitudinal brace and hand rail 43 has attached to it an angular strut 44 the ends of which extend to the bench.

Fig. 7 shows an arrangement by which the parts of the guard structure may be held together by bolts instead of by welding. The extremity of the horizontal brace 45 is bent as indicated at 46 to extend over the arched member 47 of the end guard structure. 48 is the horizontal brace of the end structure and 49, 50 pipe sections constituting the vertical brace. 51 represents the diagonal brace and 52 one of the seat boards of the bench. These parts are secured together by a bolt 53. The construction, except in this regard, is like that shown in Fig. 6.

We claim:

1. In a railway section car, the combination with the running gear and deck of the car, of guard structures providing hand-holds extending across the car from side to side thereof at opposite ends of the deck, and a longitudinal guard and bracing structure providing a hand-hold extending through the middle of the car and connecting said end guard structures. 95

2. In a railway section car, the combination with the running gear and deck of the car, of guard structures providing hand-holds at opposite ends of the deck, a longitudinal guard and bracing structure providing a hand-hold extending through the middle of the car and connecting said end guard structures, and wire mesh netting secured to the lower portions of said end guard structures. 105

3. In a railway section car, the combination with the running gear and deck of the car, of guard structures providing hand-holds at opposite ends of the deck, a longitudinal guard and bracing structure providing a hand-hold extending through the middle of the car and connecting said end guard structures, and guard strips along the edges of the deck of the car. 115

4. In a railway section car, the combination with the running gear and deck of the car, of guard structures at opposite ends of the deck comprising arched shaped metal tubular members and horizontal and vertical tubular braces secured together, and a longitudinal tubular member connecting said arched members at their middle points. 125

5. In a railway section car, the combination with the running gear and deck of the 130

car, of a bench extending lengthwise of the car, guard structures providing hand-holds at opposite ends of the car, a longitudinal guard and brace member providing a hand-
5 hold above the bench and connecting said end guard structures, and diagonal braces attached to said bench for strengthening the aforesaid structures.

6. In a railway section car, the combination with the running gear and deck of the car, of a bench extending lengthwise of the car and a guard structure comprising arched tubular members at the opposite ends of the car, horizontal and vertical braces for the
10 same, a longitudinal member extending between the center points of said arched members above the bench and braces for the aforesaid structure extending to and attached to the bench, and wire mesh netting covering the lower portions of said guard structure at the ends of the car.

7. In a railway section car, the combina-

tion with the framing of the car, of a hand rail at one end thereof and a guard rail rigidly secured to said framing below the hand rail and spaced in fixed position with respect to said hand rail.

8. In a railway section car, the combination with the framing of the car, of a hand rail at one end thereof and a guard rail below and spaced from said hand rail having a cross-sectional configuration which makes it inconvenient to grasp in lifting the car.

9. In a railway section car, the combination with the framing of the car, of a hand rail at one end of the car, round in cross-section, and a thin, flat, diagonally disposed guard rail substantially parallel with and below said hand rail which slopes from the end of the car downwardly toward the center.
